Inventor

By his Attorney Paul J. Riviere

Levi D. Miller, Jr.

UNITED STATES PATENT OFFICE.

PAUL J. RIVIERE, OF JERSEY CITY, NEW JERSEY, ASSIGNEE TO RIVIERE BRASS & BRONZE CO., A CORPORATION OF NEW YORK.

ELECTRIC-LIGHT SUPPORT.

1,289,913.

Specification of Letters Patent. Patented Dec. 31, 1918.

Application filed July 19, 1913. Serial No. 245,621.

To all whom it may concern:

Be it known that I, PAUL J. RIVIERE, a citizen of the United States, residing at Jersey City, in the county of Hudson and State of New Jersey, have invented certain new and useful improvements in Electric Light Supports, of which the following is a specification.

My invention relates to supports for electric lamps and has for its principal object to provide a support in which a plurality of electric lamps are mounted so as to be capable of being adjusted to a variety of positions.

15 A further object is to provide a single means for holding the several lamps in their adjusted positions.

Another object is to provide means for adjustably supporting a lamp shade with 20 respect to the lamps.

I attain these objects, as well as others not specifically stated, by means of the construction, arrangement and combination of parts hereinafter described.

25 In the accompanying drawings illustrating my invention;

Figure 1 is a front elevation of a support embodying my invention;

Fig. 2 is a fragmentary side elevation of 30 the adjustable mounting; and

Fig. 3 is an enlarged fragmentary view partly in section on the line 3-3 of Fig. 2.

Referring to the drawings, 1 indicates a standard which may be supported in any 35 suitable manner, as, for example, by the base 2 shown in Fig. 1. The standard is formed of two tubular sections or parts having their adjacent ends secured, at diametrically opposite points, to a ring-like member 4, which member constitutes a 40 socket for the adjustable lamp supporting arms 5. Flexible wires W extend through the standard 1 and the arms 5, as shown in Fig. 3, to carry the current to the lamps L.

45 The arms 5 are substantially J-shaped and are mounted in nipples 6 formed on the pair of oppositely located disks 7. Said disks are provided with annular flanges 8 disposed adjacent their marginal edges, and 50 which fit into the socket member 4, as seen in Fig. 3, so as to permit of rotation of the disks on said socket member. The disks are perforated axially to receive a bolt 9, having a knurled head 10 which abuts against 55 one of the pair of disks and a nut 11 which

abuts against the other. The bolt and nut serve to hold the lamp carrying arms adjustably in position.

A rod 12 fits telescopically into the upper part of the standard 1 and is provided with 60 a collar 13 to support the usual lamp shade (not shown). A collar 14 is rigidly mounted on the upper end of the standard 1 and carries a thumb-screw 15 which impinges against the rod 12 so as to hold the lamp 65 shade at any desired elevation within the range of adjustment of the rod.

As illustrated in Fig. 1 the inverted J-shaped arms 5 face or extend in opposite directions with the two lamps L lying on 70 opposite sides of the standard 1. In the extreme upper or lower adjusted position of the arms the ends thereof will strike against the sides of the standard, thus limiting the range of adjustment of each arm to an arc 75 of slightly less than 180°. This prevents the arms from being accidentally turned to such an extent as to break the feed wires.

It will be noted that by loosening the nut 11 the disks 7, which carry the lamp supporting arms, may be turned so as to adjust the lamps in different angular positions relative to the standard or to each other. It will also be observed that either lamp may be adjusted independently of the other and 85 that the single nut 11 serves to maintain both lamps in their adjusted positions.

Various changes and modifications may be made in the combination and arrangement of parts herein described, without departing from the scope of my invention as 90 pointed out in the claims.

What I claim is:

1. In an electric light support, a standard provided with a ring-like member, a 95 pair of disks revolvably mounted on opposite sides of said member, J-shaped lamp supporting arms secured to said disks, said arms being disposed on opposite sides of the standard so as to engage the latter and be 100 restricted in their movement thereby, and a bolt extending axially through the disks and ring-like member and having a nut for clampingly holding the disks against said member. 105

2. In an electric light support, a standard, a member carried by the standard below the top thereof, a pair of disks mounted on opposite sides of the member so as to turn with relation thereto, lamps carried by the disks, 110

and a single means for holding both of the disks against turning movement.

3. In an electric light support, a hollow standard, a ring-like member carried by the standard, hollow lamp carrying arms, disks supporting said arms and mounted on op-

posite sides of said member, means to adjustably secure the disks to said member, and lamp wires passing through the standard and ring-like member into the arms of 10 the disk.

P. J. RIVIERE.
